UNITED STATES PATENT OFFICE.

PATRICK ALPHONSUS MARTIN AND JOHN STANLEY, OF BIRMINGHAM, ENGLAND.

GOLF AND OTHER PLAYING BALL.

1,198,366.

Specification of Letters Patent. Patented Sept. 12, 1916.

Application filed February 24, 1916. Serial No. 80,257.

To all whom it may concern:

Be it known that we, PATRICK ALPHONSUS MARTIN and JOHN STANLEY, subjects of the King of Great Britain, residing at Birmingham, England, have invented certain new and useful Improvements in Golf and other Playing Balls, of which the following is a specification.

This invention relates to golf and other playing balls particularly of that type comprising a rubber core or center around which is wound tensioned tape or thread of rubber or other suitable material, the whole being inclosed in an outer casing or cover of gutta-percha or the like.

The object of the present invention is to provide a solid core or center for a golf or other playing ball which, by virtue of its construction, is maintained in a permanent state of compression independently of the compression produced by the exterior windings of tape or thread, thereby producing a ball which possesses enhanced "driving" powers.

According to the invention the core is composed of soft unvulcanized rubber in the form of one or more strips or windings wound upon themselves, in a state of tension, to form a nucleus or sphere maintained, by virtue of the tensioning windings of which it is composed, in a state of compression with a tendency to expand outward. Incorporated with the rubber, in the course of its manufacture is a suitable granulated material, such as emery, glass, stone, metallic filings or the like, the proportions of which may vary from a small percentage to a large percentage of the weight of the core.

Figure 1 of the accompanying drawings represents a section partly in elevation, through a golf ball constructed in accordance with the present invention. Fig. 2 is a section through the core. Fig. 3 represents in side elevation the core cut into two halves, showing the form the two halves assume. Fig. 4 is a similar view of the two halves of the core, but as seen from a position at right angles to that from which Fig. 3 is seen. Fig. 5 shows the core being wound.

In carrying out the production of the im-

proved golf ball a mass of unvulcanized rubber is mixed with a suitable granulated material such as emery, glass, stone, metallic filings, or the like in suitable proportions to give the desired weight to the ball. The mixture is then rolled or fashioned into a flat strip or tape, which is wound upon itself in a state of tension as shown in Fig. 5, into a ball or nucleus *a*, forming the core or center of the ball, which is maintained in a permanent state of compression. The presence of the granulated material lessens the molecular friction or adhesion of the rubber, so that if the core be cut into two halves the diametrical plane of each half expands outward so as to assume a part spherical surface, as seen in Figs. 3 and 4. This soft rubber core *a* has wound upon it the usual highly-tensioned windings *b* of rubber tape or thread, which further compresses the rubber center, and the whole is inclosed in the ordinary gutta-percha cover or casing *c*.

In a modification the granulated material may be omitted.

Having fully described our invention, what we desire to claim and secure by Letters Patent is:—

1. A core for a playing ball formed by a winding of tensioned unvulcanized rubber which is incorporated with a granulated weighting material, said core being maintained in a permanent state of compression.

2. A playing ball comprising a center composed of a tensioned winding of soft unvulcanized rubber, a weighting material incorporated with said rubber, an exterior winding of tensioned material upon the center, and an outer cover inclosing the core and surrounding winding, said core being maintained in a permanent state of compression independently of the surrounding winding.

In testimony whereof we have hereunto set our hands in presence of two subscribing witnesses.

PATRICK ALPHONSUS MARTIN.
JOHN STANLEY.
